Fig. 7

*Fig. 8*FIGURE 1 is a perspective view of a juvenile tractor showing my new design;

FIGURE 2 is a top plan view thereof;

FIGURE 3 is a front elevation view thereof;

FIGURE 4 is a rear elevation view thereof;

FIGURE 5 is a perspective view of the juvenile tractor wherein one front wheel is employed, the rear fenders have been omitted and the engine representation arrangement has been slightly modified;

FIGURE 6 is a top plan view thereof;

FIGURE 7 is a front elevation view thereof; and

FIGURE 8 is a rear elevation view thereof.

I claim:

The ornamental design for a juvenile tractor, substantially as shown and described.
